UNITED STATES PATENT OFFICE

GEORGE A. JOHNSON, OF FAIRFIELD, CONNECTICUT, ASSIGNOR TO THE BRYANT ELECTRIC COMPANY, OF BRIDGEPORT, CONNECTICUT, A CORPORATION OF CONNECTICUT

ELECTRICAL FITTING

Original application filed May 17, 1928, Serial No. 278,447. Divided and this application filed January 8, 1930. Serial No. 419,351.

This application is a division of my application Serial Number 278,447 filed May 17, 1928. The invention herein described and claimed has to do with a simplified construction of the casing for an electric switch or other electrical fitting. One object attained is a simple way of securing a cover on the casing by the members which are used to mount the casing, for instance in an outlet box, and in many cases also to attach a face plate to the casing. The invention also provides a way of securing a unitary switch movement in the casing.

In the accompanying drawings—

Figure 1 is a top plan view of a switch embodying this invention.

Figure 2 is a view of the same switch in side elevation.

Figure 3 is a view in side elevation with a part at one end broken away.

Figure 4 is a view in section on the line 4—4 of Figure 3.

The switch comprises three main parts, the base 11, the cover 12 and the switch movement.

The base 11 is of insulating material and has a well for the switch movement. On the corners of the base at the open end of the well are bosses 14 and, at the mid-portions of its opposite ends, larger bosses 15, these bosses serving to position the cover. The inner bottom surface of the base is recessed at 16 to permit rocking of the contact carrier.

At one end of the base are fixed terminals 17 and 18 held in place by screws extending through the wall of the base from the underside. The terminal piece 17 has a portion 21 extending upwardly and inwardly to form a knife-blade contact. Piece 18 has a similar portion 22 extending downwardly in the well in the base and inwardly as shown in Fig. 2.

At the other end of the base are terminals 23, 24 held in place by similar screws. These terminals are connected by a portion 27 which lies in the well and has an offset portion forming a contact blade 28. Extending from the terminal piece 23 inwardly and upwardly, in the same manner as does the blade 21, is a contact blade 29.

Each terminal piece has a binding screw 30 for securing the lead wire.

The cover 12 is of molded insulating material and is hollow. At the ends of the cover are projections, which engage the inner faces 55 of the bosses 15, and shoulders which rest against the bosses 14. The cover has an aperture 31 for the thumb-piece and slots for the contact blades 21 and 29.

The cover is clamped in position by ears 60 32 which serve also as a means for attaching the switch to a wall box, face plate or other support which commonly is used with switches of this type. For this latter purpose, the usual holes 33 are provided in the offset attaching portions 34 and are enlarged to permit some freedom of positioning. The ears have offsets or feet 35 which extend over the ledges 36 at the ends of the cover and thus, when the ears are secured in position on the 70 base by the screws 37 which extend through holes from the underside of the base, the cover is held tightly on the base.

Attention is called to the fact that the offsets 35 are bowed to give a certain resilience. 75 This is to accommodate the slight differences in dimensions of the cover 12 and of the parts of the base which determine the relative levels of the ledges 36 and the tops of bosses 15. These differences are avoidable only at considerable expense in manufacture but by the present construction are rendered immaterial. The resilience of the bowed offsets also gives a tighter clamping action and serves as a lock washer to keep the screws 37 80 from turning. It is to be noted that the ears should be held flat against the boss 15 to assure proper positioning of the attaching offsets 34 in the same plane parallel to that of the plate to which they are secured.

The switch movement may be of any desired form, the one shown here being a double pole toggle or tumbler switch, more fully described in my application referred to above. It has a hand-rocked U-shaped lever 50 which carries the thumb piece 56 and is pivoted at its lower end on the down legs 44 of the double arm member 40 which extends lengthwise of the base. The frame 60 that carries the switch pieces 70 is pivoted on the under side of the 100

double arm member 40 and is connected to the rocking lever 50 by a spring 65 which draws the frame 60 upward against its fulcrum and the rocking lever 50 downward against its fulcrum. When the thumb piece is moved, the lever 50 is rocked until the spring 65 is carried beyond its dead center position, whereupon its effect upon the carrier frame 60 is no longer to hold it in one extreme position but is to swing it to its other extreme with a snap action. In this way the switch members 70 are moved between their two positions engaging different sets of fixed contacts.

Near their ends, the two arms of the member 40 are connected by cross straps 42 and beyond these extend the ends 41 of the arms. The switch frame is set in the base well with the cross straps 42 resting on the inner parts 15a of the bosses 15, these inner parts being at a lower level than the main parts, and with their outer edges against the inner faces 15b of the said main parts 15. The end extensions 41 lie against the side faces of the main parts of the bosses. Thus the switch frame is held against both endwise and side-wise movement by reason of its relation to the bosses 15, straddling them as it does both from the top and from the side.

The cover 12 rests on the cross-pieces 42 and is of such dimensions that when in position on the cross-pieces its rim just clears the top edge of the base. The clearance preferably is very slight and may be so slight as not to be noticeable to the eye. The important thing is to have the cover and base rims pressed together only at the two points where the cover rests on the cross-pieces and is clamped by the ears 32. This gives a two-point mounting and prevents the strains that frequently come about when a cover is held against a base all around its rim. If the cover were not used to hold a mechanism within the base, the same principal could be employed by having a clearance between the cover and base rims except in the region of the clamping members.

The molding of the cover is greatly simplified and made less expensive by this arrangement because of the facts that no care need be taken to have the lower rim of the cover and the top rim of the base lie in a true plane, and that less material is needed in the cover to give the necessary strength. It may happen that the clearance between the base rim and the cover rim will not be uniform at all points or that there will be a contact at some points, without appreciable pressure however, but the cover will be actually pressed down only at the points where it engages the cross pieces 42.

It will be observed that as the switch movement is a unitary thing, all parts being carried by the frame 40, it is held in the base by the engagement of the cover with the cross pieces 42. No other securing devices are need-

ed. Because of this, the parts needed are fewer and the assembly is facilitated.

I claim:

1. An electrical fitting comprising a base, a cover of molded insulating material resting on the base, and an ear at each end of the base and secured thereto, each ear having a portion engaging the cover to hold the latter on the base and another portion for attaching the fitting to a support. 75

2. An electric fitting comprising a base, a cover of molded insulating material resting on the base, an ear at each end of the base and secured thereto, said ear having a bowed portion engaging the cover to hold the latter on the base and another portion for attaching the fitting to a support. 80

3. An electrical fitting comprising a base, a cover of molded insulating material for the base, a clamping member at each end of the base and secured thereto, each clamping member having a portion engaging the cover to secure it to the base, the rim of the cover being adapted to clear the rim of the base except in the region of said clamping member to give 90 a two-point mounting. 85

4. An electric switch comprising a base, a well therein, a switch movement in the well, said base having portions co-acting with portions of the switch movement to position the latter in the well, a cover of insulating material engaging portions of said switch movement, an ear at each end of the base and secured thereto, each ear having a portion engaging the cover to hold it and the switch movement portions against the base, and another portion for attaching the fitting to a support. 95 100

5. An electric switch comprising a base, a well therein, a switch movement in the well 105 having a main frame resting on said base, a cover of molded insulating material secured to the base and bearing on portions of said frame to hold the latter to the base, the rims of said cover and base having a slight clearance. 110

6. An electric switch comprising a base with a well therein and bosses at its two ends extending above its top edge, a switch frame having portions straddling said bosses to be held against all lateral movement, a cover of molded insulating material resting on portions of said frame to hold the latter to the base, said cover and base not being pressed together at other points and means securing 115 said cover to said base. 120

In testimony whereof I have signed my name to this specification.

GEORGE A. JOHNSON.
